[57] CLAIM

The ornamental design for a ocean buoy, as shown and described.

DESCRIPTION

FIG. 1 is a front elevational view of an ocean buoy showing my new design, with the rear being a mirror image;

FIG. 2 is a side elevational view thereof, with the opposite side being a mirror image;

FIG. 3 is a top plan view thereof;

FIG. 4 is a bottom plan view thereof;

FIG. 5 is a front elevational view of a second embodiment thereof with the rear being a mirror image;

FIG. 6 is a side elevational view thereof, with the opposite side being a mirror image;

FIG. 7 is a bottom plan view thereof;

FIG. 8 is a reduced perspective view taken from slightly above and between the front and side elevational views of FIGS. 1 and 2 respectively; and,

FIG. 9 is a reduced perspective view of the embodiment depicted in FIGS. 5, 6 and 7 thereof.
